Donald S. Hartwell, 52 Haverhill St., Providence, R.I.

Filed May 24, 1965, Ser. No. 85,422

Term of patent 14 years

(Cl. D83—1)

Fig. 1.

Fig. 2.

Fig. 3.

Fig. 4.

Fig. 5.

FIG. 1 is a top plan view of an electrical massager, showing my new design,

FIG. 2 is a side elevational view,

FIG. 3 is a front elevational view,

FIG. 4 is a rear elevational view, and

FIG. 5 is a perspective view thereof.

The undisclosed bottom portion of the massager is substantially plain and generally follows the contour shown in FIGS. 2 and 5 on the drawing.

I claim:

The ornamental design for an electrical massager or similar article, substantially as shown and described.
